Primary Examiner — Mary Ann Calabrese

(57) CLAIM

The ornamental design for a clothes rack, as shown and described.

DESCRIPTION

1. Clothes rack

1.1 : Perspective

1.2 : Front

1.3 : Back

1.4 : Top

1.5 : Bottom

1.6 : Right

1.7 : Left

No protection is sought for the features shown in broken lines. The clothes rack is shown with a symbolic break in its length. The appearance of any portion of the article between the break lines forms no part of the claimed design.
